DESIGN FOR A COMBINED HAIRPIN HOLDER AND FINGER RING

S. Isabelle Sohmer, New York, N. Y.

Application April 10, 1942, Serial No. 106,522

Term of patent 3½ years

To all whom it may concern:

Be it known that I, S. Isabelle Sohmer, a citizen of the United States, residing in the city, county, and State of New York, have invented a new, original, and ornamental Design for a Combined Hairpin Holder and Finger Ring, of which the following is a specification, reference being had to the accompanying drawing, forming a part thereof, in which:

Fig. 1 is a front elevational view of a combined hairpin holder and finger ring showing my new design;

Fig. 2 is a side elevational view thereof; and
Fig. 3 is a bottom plan view thereof.

I claim:

The ornamental design for a combined hairpin holder and finger ring, as shown.

S. ISABELLE SOHMER.
